UNITED STATES PATENT OFFICE.

FRANK LEWIS MORGAN, OF WASHINGTON, DISTRICT OF COLUMBIA, ASSIGNOR TO
JOHN T. UNDERWOOD, OF BROOKLYN, NEW YORK.

COMBINED TYPEWRITING AND COMPUTING MACHINE.

Application filed October 3, 1911. Serial No. 682,542.

To all whom it may concern:

Be it known that I, FRANK L. MORGAN, a citizen of the United States, residing in city of Washington, District of Columbia, have invented certain new and useful Improvements in Combined Typewriting and Computing Machines, of which the following is a specification.

My invention relates to computing machines combined with typewriting machines. More specifically, it relates to a lock for compelling the mechanism to perform a given kind of work for which it is set while writing a certain number or numbers, and means for releasing said lock to return the locked mechanism to perform its normal operation. I also provide a conspicuous tell tale to show how the mechanism is set.

I show a latch adapted to set the computing mechanism either for subtraction or addition, but normally returning it to addition, and a lock operated by the casing carrying the recording wheels. This lock can be set while writing a given number, to hold the mechanism so that it will perform subtraction; but immediately the number is written, the lock is released, and the mechanism returns to position so that it will add. In this way, it is possible for the operator to run the machine with less attention, because the normal operation of a typewriter, in general work, is in addition, subtraction being generally used only for a few moments, and my device, as has been pointed out, automatically returns the computing mechanism to the normal operation.

Other features and advantages will hereinafter appear.

In the accompanying drawings,

Figure 1 represents my attachment as applied to an adding machine attached to a typewriter, showing only a portion of the typewriter.

Figure 2 is a perspective view of some of the parts on a larger scale.

Figure 3 is a perspective view of some of the parts set in a different position.

Figure 4 is a perspective view of the locking mechanism.

Figure 4 shows the same parts as Figure 3, but in their operative positions at the time that the typewriter carriage is operative on the device.

Figure 5 shows the latch in its normal position.

Figure 6 shows the latch of the lock between its two operative positions.

Figure 7 shows the gearing set for subtraction.

Figure 8 shows the gearing set for addition.

Figure 9 is a view of the bottom of the casing carrying the dials.

Figure 10 illustrates my attachment as applied to an adding machine attached to a Remington front-strike typewriter.

In the drawings, 1 is the main frame of the typewriter, on which runs a carriage 2 from which is supported a bar 3 carrying a rack bar 4, on which is supported a casing 5 carrying the dials 6 of what is commercially known as a "Wahl" computing machine. This casing is adjustable along the rack 4 by means of a latch 7, and is held at the bottom on a bar 8.

On the main frame of the typewriter, is carried a driving mechanism for said dials, consisting of a master wheel 9 on a shaft 10 which is turned by a segment wheel 11. Said segment wheel is rotated in the usual way, Figure 10, to carry figures from the numeral keys of the typewriter to the computing mechanism.

While performing addition, the key-driven segment 11, Figure 8, meshes with a pinion 12, which is mounted upon and turns the master wheel shaft 10. Computation wheels 44, in the casing 5, are successively engaged by the master wheel 9 as the typewriter carriage makes its letter-feeding movements, whereby the dial wheels are turned successively.

In order to perform subtraction, a handle 19 is shifted toward the left or to the Figure 7 position, to disconnect said master wheel pinion 12 from the key-operated segment 11, and simultaneously connect 11 to 12 by means of a back-gearing device, so that pinion 12 will rotate in the opposite direction at the key strokes. The back-gearing device comprises pinions 15 and 16. Pinion 15 is always in mesh with said pinion 12, but turns idly during the adding operation; and pinion 16 is rigidly connected to 15 by means of a sleeve 14, and also turns idly during the addition operation. But it will be seen that when pinions 15 and 16 are shifted axially to the Figure 7 position, the pinion 16 is brought into mesh with the key-driven segment 11, and by means of the

pinion 15 rotates the master wheel pinion 12, so that the master wheel 9 is turned in abnormal or subtraction direction.

- For the purpose of subtraction, therefore, 5 the handle 19 is connected to shift the pinion 12 out of engagement with the key-driven segment 11, and also to shift the pinion 16 into mesh with said segment 11; the pinion 16 being also shifted with the pinion 12. 10 Said handle 19 is fixed upon an arbor 17, which carries the pinions 15 and 16; the latter having the usual pin-and-groove connection to the arbor so as to shift therewith, while turning freely thereon. A yoke 18 15 connects the members 15, 14, 16 with the hub of the pinion 12, so as to shift the latter simultaneously; the pinion 12 being splined to the master-wheel shaft 10 to permit such longitudinal shifting of the pinion. 20 The mechanism so far recited is common in the Wahl adding machine, and there is also usually provided in said Wahl machine a plate 83, having notches 31 and 32 into either of which may snap the edge or tooth 25 of arm 18, which carries said handle 19; a spring 18^a being usually employed to hold the tooth or catch 30 down in the notch. The operator has been accustomed to lift the handle 19 to clear the notches 31 and 32, 30 and has then pulled the handle either to the left or right, to set the machine for either subtracting or adding, and has released the handle 19; and the tooth 30 of arm 18, by means of said spring 18^a has been caused to 35 catch in the notch to maintain the machine in either adding or subtracting condition.

- In order to avoid mistakes occurring by reason of the operator forgetting to restore the machine to addition after it has been used for subtraction, I provide a spring 28, which is in the nature of a returning spring, and tends always to return the arbor 17 and the back-gearing device to normal adding position, seen in Figure 8; and I arrange 40 for such return to be accomplished automatically after the completion of the operation of subtracting a number. When the handle 19 is shifted to the left, the spring 28 is compressed so as to return the parts; 45 but such return is automatically delayed or prevented until the completion of the writing of a number. I provide a normally ineffective latch 37, which is depressible by means of a bar 39 provided upon the under surface of the casing 5 of the totalizer or adding head. As the typewriter carriage travels and the adding head approaches the position for computation, the latch 37 is depressed by said bar 39. This latch may be 50 in the form of a bend made on the upper end of a vertical plate 25 and rounded off at both corners 38 to give a cam effect. Upon the plate 25 is an ear 25^a, having a slot 24, which engages an arm 21 upon a rock shaft 55 22, the latter also having an arm 21, which

has a pin-and-slot connection 20, Figures 5 and 6, with the aforesaid reversing arm 18.

The operator may lift the handle 19 against the tension of spring 18^a, sufficiently to release it from the notch 32, and may then push the handle towards the left, carrying with it the arm 18, arbor 17, and back gears 15 and 16 to the Figure 7 position; whereupon the operator may drop catch or tooth 30 of arm 18 into the subtraction notch 31; said spring 18^a operating to hold it in the notch. The little play of the arm 18, which is necessary for entering and leaving the notches, is provided by the pin-and-slot connection at 20. The arms 18 and 21 are held by the heads of the pivot at 20 so that arbor 17 and rock-shaft 22 move endwise together. When the operator sets the arm 18 into the notch 31, it does not quite touch the bottom of the notch, as seen at Figure 6, because the pin 20 prevents the arm 18 from dropping so far; but the spring 18^a holds down the arm 18.

During the writing and subtraction of the number the totalizer casing carries down (Figure 4^a) and holds down the latch device 37, so that the parts remain in subtraction position. The depression of arm 21 by means of the part 37, permits the spring 18^a to carry the arm 18 a little farther into the notch, as at Figure 4^a. After the completion of the writing of the number, the totalizer travels past the latch 37 and releases the same, and a spring 34, which is tensioned by the down stroke of the latch plate 25, (one end of said spring connected to a pin 35 projecting from latch plate 25, and the other end of said spring connected to a pin 36, which projects from a grooved guide or guide plate fixed upon the framework of the typewriting machine, and upon which the plate 25 slides up and down), lifts the latch plate 25, together with the arm 21, thus rocking the shaft 22 and causing arm 21 to strike up the arm 18 so far that tooth 30 of the latter is carried out of the subtraction notch 31, whereupon the spring 28 (which is coiled around the rock shaft 22 and compressed between a collar 27 on said rock shaft and a part of the framework) force the rock shaft 22 endwise (the slot 24 being long enough to permit this movement), and carries the arm 18, arbor 17 and back gears 15 and 16, together with the pinion 12, over to the addition position at Figure 8. Upon the return of the carriage to begin a new line, the casing 5 depresses the latch 37 idle, but the latter returns after the passage of the carriage.

The application of my attachment to a front-strike Remington typewriter is shown in Figure 10, in which the numeral keys and alphabet keys are indicated at 45 and 46 respectively, each key controlling through its lever 47, link 48, bell crank 49 and link

50, a typo-bar 51, bearing the type 52. The depression of a key causes its type 52 to strike the platen 53. The operation of the key lever effects also the release of the typewriter-carriage escapement through the adjustable screw 54, universal bar 55, bell crank 56, link 57, bell crank 58, dog 59, ratchets 60, and the pinion 61, meshing with the rack 62 fixed to the typewriter carriage 2. Each of 10 the numeral keys is connected to the segment wheel 11 through the link 63, plate 64, pin-and-slot connection 65, cam arm 66, and extension 67 on the actuating lever 68; the several actuating levers 68 are rigidly 15 mounted upon the rock shaft 69 which carries the segment wheel 11 heretofore described. Connections similar to these are found in the Wahl Patents 893,718 and 893,719, dated July 21, 1908.

20. In the casing 26 of the drive mechanism, is provided a window 40, through which the operator can see a tell-tale 41, carried on shaft 22, showing at a glance what operation the computing mechanism is set for. For 25 this purpose, the tell-tale 41 is provided with a portion 42 colored black, which will be visible when the computing mechanism is set for addition; and a portion 43 colored red, which will be visible when the computing 30 mechanism is set for subtraction.

It will be seen that my invention is not limited to a mere adding and subtracting mechanism, or to the type of computing device shown, but can be applied to other machines which are adapted to be converted to perform more than one kind of work, one of which it is desired to do only temporarily.

Variations may be resorted to within the scope of the invention, and portions of the 40 improvements may be used without others.

Having thus described my invention, I claim:

1. In a combined typewriting and computing machine, the combination of a carriage 45 carrying a casing, recording mechanism in the casing, mechanism on the main frame for driving said recording mechanism, means for automatically converting said driving mechanism, a latch holding said driving mechanism to perform a given kind of work, means for automatically releasing said latch, and a movable arm on the main frame adapted to bear against said casing to hold 50 said latch operative while said recording mechanism engages the driving mechanism.

2. In a combined typewriting and computing machine, the combination of a carriage carrying a casing, recording mechanism in the casing, mechanism on the main 55 frame for driving said recording mechanism, a gear for reversing said driving mechanism, a spring for normally holding said reversing gear inoperative, a latch for locking said reversing gear in operative or inoperative position, a spring tending to release said latch,

and an arm adapted to be depressed by the casing to hold said second spring inoperative.

3. In a combined typewriting and computing machine, the combination of a carriage carrying a casing, recording mechanism in the casing, mechanism on the main frame for driving said recording mechanism, a gear for reversing said driving mechanism, a handle shifting said gear, a shaft carrying an arm pivoted to said handle, a spring tending to move said shaft to carry said gear to a given position, and an arm rotating said shaft to depress said handle into notches adapted to latch it.

4. In a combined typewriting and computing machine, the combination of a carriage carrying a casing, recording mechanism in the casing, mechanism on the main frame for driving said recording mechanism, a gear for reversing said driving mechanism, a handle shifting said gear, a shaft carrying an arm pivoted to said handle, a spring tending to move said shaft to carry said gear to a given position, an arm rotating said shaft to depress said handle into notches adapted to latch it, a projection embracing said arm, a lock operating arm to move said first arm, and a spring tending to move said operating arm.

5. In a combined typewriting and computing machine, the combination of a carriage carrying a casing, computing mechanism in the casing, a casing on the main frame, driving mechanism in the second casing co-operating with the mechanism in the first casing, means for converting one of said mechanisms, automatic means tending to bring said convertible mechanism to perform a given operation, an arm moved by the approach of the casings, a shaft turned by said arm against the action of a spring, a latch held normally open by said spring and adapted to be closed by the movement of said arm, and a shaft controlled by said latch to move the converting means.

6. In a combined typewriting and computing machine, the combination of means for setting said computing mechanism to add or subtract, a casing conspicuously set in front of the machine containing part of 115 said mechanism, a window in said casing, and a tell-tale in such window to show how the mechanism is set.

7. The combination of a key-controlled drive wheel, a master-wheel shaft to be 120 driven thereby, computing wheels operable by said master-wheel, a slideable gear on said shaft adapted to mesh with said drive wheel, a slideable shaft carrying said slideable gear with it and also two gear wheels fixed on a 125 sleeve on itself, one meshing with said slideable gear, and one adapted to mesh with said drive wheel, a handle moving said slideable shaft, notches to hold said handle, a spring normally pulling said handle above 130

- one notch, a second spring holding said handle out of said notches, and an arm to depress said arm into a notch.
8. The combination of a master element, a totalizer element, a carriage connected to one of said elements, a device manually operable for shifting the mechanism from addition condition to subtracting condition, a catch for holding the shiftable device in subtraction position, a spring tending to release said catch, means dependent upon the carriage for restraining said spring, said spring being released by the movement of the carriage at the completion of the subtraction operation, and a spring normally restrained by said catch and operating upon the release of said catch to restore the shiftable device to addition position.
9. The combination of a typewriter carriage, a totalizer, a master wheel, a key-controlled driver connected to said master wheel, back gearing between the driver and the master wheel, a shiftable device to operate said back gearing, a spring for returning said shiftable device, a latch set or controlled by the carriage for preventing the return of said shiftable device by said spring, and a spring to return said latch after the movement of the carriage, and permit the first spring to return the shiftable device and reset the machine for addition.
10. In a combined typewriting and computing machine, the combination of a movable carriage, a computing mechanism movable thereby, a reversible master wheel for actuating said computing mechanism, a switch handle for reversing the direction of said master wheel, and a cam member comprising a bent plate, adapted to be moved by the carriage to depress said switch handle.
11. The combination of a member having a tooth 30 to engage subtraction notch 32, a handle connected to said tooth member, a back-gearing device operated by said handle, a master wheel controlled by said back-gearing device, computing wheels operated by said master wheel, a spring tending to return the back-gearing device to normal addition position, a latch mechanism automatically operated at the computing operation and automatically released at the conclusion of the computing operation whereby said spring returns the parts to position for addition, a carriage, a part on said carriage for setting said latch mechanism, said back-gearing device being shiftable by said handle after the setting of said latch mechanism, and a tooth member having an independent spring for holding it in the subtraction notch.
12. The combination of a member having a tooth 30 to engage subtraction notch 32, a handle connected to said tooth member, a back-gearing device operated by said handle, a master wheel controlled by said master wheel, computing wheels operated by said master wheel, a spring tending to return the back-gearing device to normal addition position, a latch mechanism automatically operated at the computing operation and automatically released at the conclusion of the computing operation whereby said spring returns the parts to position for addition, a carriage, a part on said carriage for setting said latch mechanism, said back-gearing device being shiftable by said handle after the setting of said latch mechanism, and a tooth member having an independent spring for holding it in the subtraction notch.
13. In a combined typewriting and computing machine, the combination of means for setting said computing mechanism to add or subtract, a casing conspicuously set in front of the machine containing part of said mechanism, a window in said casing, a tell-tale in such window to show how the mechanism is set, and means extending outside of said casing to operate said setting means.
14. In a computing machine, the combination of a register, an actuator, a traveling carriage for bringing one denomination after another under the control of the actuator, means for manually setting the mechanism to change the character of the arithmetical operation, a device for automatically returning to initial position the mechanism so set, means for holding said return device against action, a device for automatically releasing said return device after the register has passed the computing zone, and means on the carriage for holding said release device against action during the passage of the register through the computing zone.
15. In a computing machine, the combination of a register, an actuator, a traveling carriage for bringing one denomination after another under the control of the actuator, means for manually setting the mechanism to change the character of the arithmetical operation, a device for automatically returning to initial position the mechanism so set, means for holding said return device against action, a device for automatically releasing said return device after the register has passed the computing zone, means on the carriage for holding said release device against action during the passage of the register through the computing zone, and means whereby the mechanism may be manually set to change the character of the arithmetical operation while the register is in the computing zone.
16. In a computing machine, the combination of a register, an actuator, a traveling carriage for bringing one denomination after another under the control of the actuator, means for manually setting the mechanism to change the character of the arithmetical operation, a device for automatically returning to initial position the mechanism so set, means for holding said return device against action, a device for automatically releasing said return device after the register has passed the computing zone, and means whereby the mechanism may be manually set to change the character of the arithmetical operation while the register is in the computing zone.

- another under the control of the actuator, the register being adjustable with relation to the travel of the carriage, means for manually setting the mechanism to change the 5 character of the arithmetical operation, a device for automatically returning to initial position the mechanism so set, means for holding said return device against action, a device for automatically releasing said return device after the register has passed the computing zone, and means on the carriage for holding said release device against action during the passage of the register through the computing zone.
- 10 17. In a computing machine, the combination of a register, an actuator, a traveling carriage for bringing one denomination after another under the control of the actuator, means for manually setting the mechanism 20 to change the character of the arithmetical operation from addition to subtraction, a device for automatically returning to initial position the mechanism so set, means for holding said return device against action, a device for automatically releasing said return device after the register has passed the computing zone, means on the carriage for holding said release device against action during the passage of the register through 25 the computing zone, and means whereby the 30
- mechanism may be manually set to change the character of the arithmetical operation from addition to subtraction and vice versa while the register is in the computing zone.
18. In a computing machine, the combination of a register, an actuator, a traveling carriage for bringing one denomination after another of the register under the control of the actuator, gearing from the actuator to the register for driving the latter in a direction to perform one character of arithmetical operation, back gearing adapted to connect the actuator to the register for driving the latter in the other direction to perform an arithmetical operation of another character, 35 means for shifting and locking the back-gearing mechanism to render the same operative or inoperative, a spring tending to throw the back-gearing mechanism to operative position, and a latch mechanism automatically set by the movement of the carriage preliminary to the computing operation, and automatically released to permit the spring to shift the back-gearing mechanism at the conclusion of the computing 40 operation.
